SEAMING TAPE

Paul D. Wright, New York, N. Y., assignor to United States Rubber Company, New York, N. Y., a corporation of New Jersey

Application April 25, 1955, Serial No. 503,699

6 Claims. (Cl. 28—78)

This invention relates to a seaming tape comprising a paper backing strip to which transversely extending lengths of untwisted yarns are attached by longitudinal rows of stitches.

The tape embodying this invention is useful for uniting sheet material to resist forces acting transversely of the seam or joint. For example the tape may be used to join cardboard and to reinforce seams and corners in cardboard boxes. Where the paper backing of the tape is extensible longitudinally of the seaming tape, it is particularly useful for forming butt joints between the edges of two pieces of carpet. In such constructions the transversely extending yarns are adhesively united to the edges to be joined and they secure the seams against transverse separation. For that purpose a strong adhesive bond is required, and it is desirable that the yarns have little or no extensibility under the load to which they may be subjected in the seam.

Yarns of low extensibility and high strength are obtained by employing untwisted yarns made of very long or substantially continuous filaments. Heretofore, such yarns containing relatively fine filaments have been used as transverse members in seaming tapes, but in order to secure each of the filaments of the yarn to the paper strip base, the yarns were saturated with an adhesive and then adhered to the paper strip. This procedure has the disadvantages of stiffening the tape, and increasing the labor and cost of the yarn. Furthermore, this pretreatment of the yarn with the adhesive resulted in a weaker bond between the yarn and the parts to be seamed together by the subsequent addition of the adhesive to form the seam, because the additional adhesive could not penetrate between the filaments, and only formed a surface union with the adhesive saturated yarns instead of being interlocked with the filaments of yarn.

In accordance with applicant's invention the untwisted yarns of low extensibility and high strength are made of long or substantially continuous fine filaments, and the yarns are mechanically attached to the paper backing by longitudinal rows of stitches, which envelop or extend over and secure all of the filaments to the paper backing without saturating the yarns with any filling material, such as an adhesive.

Therefore, the additional labor and cost of pretreating the yarns are eliminated and the interstices between the filaments are left open to receive the adhesive to be finally added to the tape in forming the seam between two parts to be united. In forming the seam the adhesive is applied to the transverse yarns, and it penetrates into the interstices between the filaments thereof and between the yarns to the paper backing, which protects its supporting surface from the adhesive. The freshly saturated and adhesively coated yarns, and the margins of the parts to be joined are then pressed together. A strong bond is thus formed between the yarns and the margins of such joined parts by virtue of the single unitary application of the adhesive which penetrates between the filaments and thereby forms a me-

2

chanical lock therewith, as well as a surface bond with the filaments.

The invention, its objects and advantages are further described in reference to the accompanying drawings, in which:

- 5 Fig. 1 is a top plan view of a seaming tape embodying this invention, in which the method of using the tape for seaming together the edges of two pieces of carpet is illustrated; and
- 10 Fig. 2 is a diagrammatic illustration of the tape and the method of making it.
- 15 Referring to Fig. 1, the tape 10 comprises a strip of paper 11, to which transversely extending lengths 12 of yarns 13 are attached by longitudinal rows 14 of stitches. The yarn 13 is made in the form of an untwisted ribbon of long, or substantially continuous filaments 15, which may for example be made of rayon, nylon, glass or silk. The term "untwisted yarn" is used herein to include a slight twist to permit greater ease in handling. For example, the twist may be about one turn per inch. The filaments 15 are not twisted together and are formed into a thin flat ribbon-like band to obtain the high tensile strength and low stretch required to resist the transverse forces to which the tape may be subjected in the seam formed by the tape.
- 20 The paper backing strip 11 may be made of suitable paper stock, and where the seaming tape is to be used for forming a carpet seam, such paper is creped by forming transverse crinkles 16 therein to render it extensible in the lengthwise direction of the tape.
- 25 It has been found that where the paper is creped, a 40 to 60 pound weight of kraft paper is satisfactory, but of course heavier or lighter weights may be used depending upon the purpose for which the tape is to be used.
- 30 In any event the paper should be sufficiently heavy to retain the rows 14 of stitches, and the stitches should be sufficiently long as not to form a continuous cut in the paper along the individual rows.
- 35 The rows 14 of stitches are made of textile threads, and they are preferably formed on a chain stitch machine. At least two rows 14 of the stitches extend along the outer margin of the lengths 12 of the yarns 13, and as many intermediate rows are used as may be required to hold the lengths 12 to the paper 11.
- 40 The seaming tape 11 may be made as shown in Fig. 2, in which five rows 14 of stitches 17 are used to secure the lengths 12 of the two oppositely extending yarns 13 to the strip of paper 11. In the manufacture of the tape two cones or other units 18 are mounted above the strip of paper 11, and a yarn 13 from each cone is threaded through an eye 19 in the transversely reciprocating carriers, 20, 21, and are tied together at 21' behind the row of needles of the sewing machine, which are then extending downwardly through the paper 11 to form the holes 22. The reciprocating arms 20, 21 move above and across the paper 11 in front of the needles, and carry the yarns 13 transversely of the paper 11 forming loops 23 around each of the end needles while all of the needles remain down through the paper 11. The arm 21 passes over the arm 20, and when they approach the ends of their strokes a downwardly extending projection 24 on arm 21 and an upwardly extending projection 24' on the arm 20 strike rearwardly inclined stationary cam surfaces 25 which throw the yarns 13 against the needles 26 and the eyes 19 behind the needles 26. After two such lengths 12 of the yarns 13 have been carried in front of the needles 26, they move upwardly, and the yarns 13 jump to the rear of the needles, and paper 11 is fed underneath the needles. When the needles come down, they pass over two lengths 12 of the yarns.
- 45 50 55 60 65 70 The arms 20, 21 are again reciprocated while the needles are down, and the next stitch 17 is then made. In the

manufacture of the tape 10 as just described each of the stitches 17 include two of the lengths 12 of the yarns 13, and each stitch of the two end rows 14 extends through each of the end loops 23 formed in the yarns 13. The lengths 12 are thus secured to the paper 11 close to each other.

Fig. 1 illustrates the use of the tape 10 for securing the edges 27 of two pieces of carpet 28 together. In this operation the seaming tape 10 is placed on the floor, and a flexible adhesive, such as latex is coated onto the lengths 12 of the yarns 13. The edges 27 of the carpet 28 are abutted together and folded down onto the tape 10 along the center line 29 thereof so as to hold together the seam 30 of the carpet along such line. After the cement has dried, the carpet may be stretched in place. The longitudinal extensibility of the paper 11 and rows 14 of stitches 17 permits the carpet to be stretched lengthwise without rupturing the tape. Any stretch of the carpet transversely of the seam 30 may occur without interference of the tape 10, and the substantially inextensible lengths 12 of the yarns 13 being adhered to the carpet 28, they will prevent the seam 30 from opening up.

While the preferred form of this invention has been described herein, it will be understood that changes may be made without departing from the spirit of the invention, and it is intended to cover any changes coming within the scope of the claims.

Having thus described my invention, what I claim and desire to protect by Letters Patent is:

1. A carpet seaming tape comprising a strip of paper, untwisted yarns made of relatively fine substantially continuous filaments extending transversely of said strip, and a plurality of longitudinal rows of stitches securing said yarns to said paper strip.

2. A seaming tape comprising a strip of paper, continuous untwisted yarns extending transversely of said strip in a back and forth path making loops near the margin of said strip on each side thereof, and said yarns being secured to said paper by longitudinal rows of stitches.

3. A carpet seaming tape comprising a strip of longitudinally extensible paper, untwisted yarns made of substantially continuous synthetic filaments extending transversely of said strip, and longitudinal extensible rows of stitches securing said yarns to said paper strip whereby the top surface of said yarns are exposed throughout their length, excepting where they are crossed by said rows of stitches.

4. A carpet seaming tape comprising a strip of lon-

itudinally extensible paper having crimps therein extending transversely of said strip, continuous untwisted yarns made of substantially continuous synthetic filaments extending transversely of said strip in a back and forth path having loops therein at each side of said strip spaced from the border thereof, and longitudinal extensible rows of stitches securing said yarns to said paper strip whereby the top surface of said yarns are exposed throughout their length, excepting where they are crossed by said rows of stitches.

5. A seaming tape comprising a strip of paper, two yarns extending in opposite directions transversely of said strip in a continuous path and having loops formed in each yarn near each side margin of said paper, longitudinal rows of stitches securing said yarns to said strip, at least two of said rows of stitches extending along said loops, each stitch of said last mentioned rows passing through each of said loops, each of said stitches spanning the adjacent sides of adjacent loops formed in said opposite extending separate yarns.

6. A carpet seaming tape comprising a strip of longitudinally extensible paper having crimps extending transversely thereof, two untwisted yarns extending in opposite directions transversely of said strip in a continuous back and forth path having loops formed in the path of each yarn near each side margin of said paper, extensible rows of stitches extending across said transverse yarns, at least two of said rows of stitches extending across said loops at each of said side margins of said paper, each stitch in said last mentioned rows of stitches passing through each of said loops and spanning the adjacent sides of the adjacent loops formed in the path of said oppositely extending separate yarns, and the surface of said yarns being exposed to receive adhesive into the interstices between said filaments of each yarn and into the interstices between said yarns.
